UNITED STATES PATENT OFFICE.

SIMEON A. YOUNG, OF LOS ANGELES, CALIFORNIA.

FILAMENT SWITCH.

Application filed June 1, 1925. Serial No. 33,933.

My invention relates to electric switches and more particularly to a special form of electric switch designed for use in connection with radio receiving sets.

5 The main object of my invention is to provide an electric switch suitable for mounting on the instrument panel of a radio receiving set, so that it may be connected in the battery circuit, supplying current to the filaments of the vacuum tubes.

Another object is to provide a filament switch of the character described which may be adjusted for panels of different thicknesses; which can be easily mounted, and 15 which is simple and inexpensive to make and which is convenient to operate.

Other objects and advantages will appear hereinafter and while I show herewith and will describe a preferred form of construction, I desire to be understood that I do not limit my invention to such preferred form but that various changes and adaptations may be made therein without departing from the spirit of my invention as hereinafter claimed.

Referring to the drawings which accompany this specification and form a part thereof:

Fig. 1 is a fragmentary view of a front 30 panel in a receiving set case with a filament switch embodying the principles of my invention mounted thereon.

Fig. 2 is a rear view of the switch shown in Fig. 1 in its open position, and a partial 35 diagram of a filament circuit illustrating the connection of the switch therein.

Fig. 3 is a similar view to that shown in Fig. 2, showing the switch in its closed position.

40 Fig. 4 is an enlarged sectional view of the switch taken on line 4—4 of Fig. 1.

Fig. 5 is an enlarged lower-end view of the switch shown in Fig. 1, as seen in a section taken through the panel approximately on the line 5—5 of that figure.

The various parts of my filament switch as designated by the reference numerals, are as follows:

A metal mounting plate 10, with a screw-threaded aperture 11 near one end of its ends, has a transverse insulating plate 12 and an insulating block 13 secured to the other end thereof by rivets 14 extending therethrough, the insulating plate coinciding in length with the width of the mounting plate and the insulating block being suffi-

ciently shorter to form angles 15 between them at their ends. Leaf springs 16 and 17 are held in these angles by fastening screws 18 which extend through them into the ends 60 of block 13, so that they are completely insulated from each other and from mounting plate 10. The length of the springs is such that they extend beyond the insulating block and form lugs 19 in which apertures 20 are made to receive the battery circuit conductors. Their other ends extend parallel to the mounting plate somewhat beyond aperture 11, spring 16 being slightly longer than spring 17 and both having their ends 70 bent inwardly to form right angled hooks 21, the purpose of which will presently appear.

An externally screw-threaded sleeve 22 with a hexagonal head 23, made integral 75 therewith, extends through aperture 11 and engages the threads thereof to hold mounting plate 10 against the inner side of the panel 24 of a casing, there being an aperture 25 in the panel to receive the sleeve. A 80 washer 26 is placed on the sleeve under head 23 to engage the outer side of the panel. A stub shaft 27, having a head 28 on its outer end which rests against hexagonal head 23, extends through sleeve 22 and a lozenge-shaped contact cam 29, having an aperture 30 to receive the projecting inner end 31 of shaft 27, is clamped on said projecting end by a set screw 32, so that it turns with the stub-shaft, there being an insulated handle 33 fixed to head 28 of the shaft by which it may be turned. Cam 29 is so adjusted that one of its points 34 is in continuous contact with spring 16 while its other point 35 makes or breaks contact with spring 17 when the shaft is turned.

Sleeve 22 and stub-shaft 27, are made of a length to permit adjustment for use with panels of different thicknesses and the manner of attaching cam 29 to the shaft also provides for such adjustment, besides allowing for the adjustment of handle 33 in any preferred position about the axis of the shaft.

The operation of my switch is clearly shown in Figs. 1, 2, and 3. It is connected 105 in one side of the "A-battery" circuit, preferably between the negative pole of the battery 36 and the return conductor 37 common to filaments 38 of one or more vacuum tubes. When the switch is in its open position, as shown in Fig. 2, contact point 34 of cam 29 engages hook 21 of spring 16 while

contact point 35 falls short of spring 17 far enough to leave a gap 39 therebetween. Cam 29 is held in this position by the combined action of the hook and spring, the former 5 preventing the cam from turning in one direction and the pressure of the latter preventing the turning thereof in the other direction. When the switch is turned into its closed position, as shown in Fig. 3, contact point 35 engages spring 17 and springs 10 16 and 17 both yield outwardly until point 35 comes into engagement with hook 21 of spring 17. Cam 29 is held in this closed position by the combined action of hook 21 15 and both springs, the pressure of which acts on opposite sides of the shaft axis to hold the cam from turning into its open position. In its closed position the cam serves as a conductor between the two springs, and 20 causes current to flow through the filaments of the vacuum tubes.

Having thus illustrated and described my invention I claim:

In an electric switch, a pair of contacts consisting of leaf springs having substantially straight body portions and end hooks, a block of insulating material to opposite sides of which the body portions of said leaf springs are secured in a flatwise manner, and a manually rotatable switch element having 25 contact points, one of said points being continuously in engagement with one of said springs and the other point being movable into and out of engagement with the other of said springs, said hooks limiting the 30 amount of rotation of said manually operable element, said springs having sufficient resiliency between their free ends and their points of attachment to said block to hold them at all times in proper operative 35 relation to said rotatable switch element.
